R. H. ROBERTS AND P. N. KINGSWELL.

FASTENER FOR LIDS OF CASES.

APPLICATION FILED JAN. 4, 1919.

Patented July 12, 1921.

1,384,151.

FIG. 4.

Inventors:
Richard Henry Roberts & Percy Nicol Kingswell
per H. W. Plecker
Attorney.

UNITED STATES PATENT OFFICE.

RICHARD HENRY ROBERTS, OF HENDERSON, AND PERCY NICHOL KINGSWELL, OF EPSOM, AUCKLAND, NEW ZEALAND.

FASTENER FOR LIDS OF CASES.

1,384,151.

Specification of Letters Patent. Patented July 12, 1921.

Application filed January 4, 1919. Serial No. 269,678.

To all whom it may concern:

Be it known that we, RICHARD HENRY ROBERTS and PERCY NICHOL KINGSWELL, both citizens of the Dominion of New Zealand, and residing at "Farmley Tyas," Te Atatu, Henderson, and Golf Road, Epsom, Auckland, respectively, have invented certain new and useful Improvements in Fasteners for Lids or Cases, of which the following is a specification.

This invention relates to means for fastening lids of cases and more particularly the lids of fruit cases, and to that kind of fastening means comprising a pin or pins rotatable in the end of the case and in a slot or slots in the lid and having a substantially right angled member or members adapted to engage and fasten the lid.

According to the present invention, in fastening means of the said kind, the head or right angled member of the pin or of each pin is adapted, when turned toward the locked position, to bear down upon the lid with increasing pressure as it is further turned toward said position. This action of the pin can be effected in various ways, for example, by suitably sloping the surface on which the right angled member bears while being turned into the locked position, or by arranging the shank of the pin so that the axis of turning is not perpendicular to the bearing surface the latter being parallel to the lid surface, or by providing the pin with a screwed shank adapted to draw the pin bodily downward as it is turned into locked position, and thereby to force the right angled member with increasing pressure against the lid.

The drawing herewith illustrates the invention:—

Figure 1, is a perspective view of a case embodying the invention,

Fig. 2, is a front elevation,

Fig. 3, a longitudinal sectional elevation, and

Fig. 4, a plan showing one embodiment of the invention,

Fig. 5, is a sectional elevation showing another embodiment of the invention,

Fig. 6, is a sectional elevation showing another embodiment of the invention, and

Fig. 7, is a perspective view showing two fasteners on a single case.

Referring more particularly to Figs. 1, 2,

3, and 4 the lid 1 of the case 2 has battens 55 3 and 4 fixed across the top at its ends, and slots or notches 5 and 6 are made through the lid 1 and the battens 3 and 4 respectively. A nail 7 having a head 8 of large diameter is driven into the end 9 of the 60 case 2 and is engaged by the slot 6, while the head 8 retains the lid.

A pin 10, turnable in a hole 11 made in the end 12 of the case 2, has a right angled member 13 at its lower end engaging the 65 top of a mortise 14, and at its upper end is engaged by the slot 5, where another right angled member 15 is sunk in a recess 16 formed in the batten 3, and engages the same. The member 15 is capable of being 70 turned into line with the notches 5 when the lid may be raised clear of the pin 10 and withdrawn from the nail 7.

A mortise 17 is made in the end 9, and the case is readily handled by passing the 75 fingers into the mortises 14 and 17.

Referring to Fig. 5, the lower end of the pin 10 is riveted upon a washer 18, which engages the top of the mortise 14.

Referring to Figs. 6 and 9, the lower end 80 of the pin 10 is screw threaded and screwed into the end 12 of the case, so that when the member 15 is turned rearwardly into the position shown the said member bears down upon the lid with increasing pressure 85 as it is further turned toward the locked position.

For a similar reason the bottom 21 of the recess 16 is made to slope as shown in Figs. 2 and 3, and in Fig. 5 the pin 10 is made 90 to slope as shown so that its axis of rotation is not perpendicular to the bottom of the recess on which the member 15 bears, said bottom being parallel to the lid surface and in each case the member 15 when turned 95 rearwardly will grip the lid with gradually increasing pressure, and when turned forwardly gives clearance to the lid when the case is to be opened.

A label 24 as shown by dotted lines in 100 Fig. 5 can be pasted over the member 15 to the batten 3 and end 12 to show that the case has not been opened by an unauthorized person. The label may bear the trade mark of the producer.

What we do claim and desire to secure by Letters Patent of the United States is:—

1. A fastener for lids of cases, compris-

ing a headed nail; projecting from one end of a case and engaged by a notch made in one end of a lid, and a pin turnable in the other end of the case and having a right angled member which is engaged by a notch in the other end of the lid and when the pin is turned toward the locked position bears down upon the lid with increasing pressure as it is further turned toward the locked position.

2. A fastener for lids of cases, comprising a headed nail projecting from one end of a case and engaged by a notch made in one end of a lid, and a pin turnable in the other end of the case having a right angled member at its lower end within a mortise formed in the end of the case, and having another right angled member at its upper end which is engaged by a notch in the other end of the lid and when the pin is turned toward the locked position bears down upon

the lid with increasing pressure as it is further turned toward the locked position.

3. A fastener for lids of cases, comprising a headed nail projecting from one end of a case and engaged by a notch made in one end of a lid, a pin turnable in the other end of the case and having a right angled member and being engaged by a notch in the other end of the lid, the said right angled member lying in a sloping recess formed in the lid, so that it bears down upon the lid with increasing pressure as it is turned toward the locked position.

In testimony whereof we have signed our names to this specification in the presence of two witnesses.

RICHARD HENRY ROBERTS.
PERCY NICHOL KINGSWELL.
